UNITED STATES PATENT OFFICE.

WILLIAM H. SOLEY, OF PHILADELPHIA, PENNSYLVANIA, ASSIGNOR OF TWO-THIRDS TO FRANK SOLEY AND JAMES WOLSTENCROFT, BOTH OF SAME PLACE.

THERMOTIC CIRCUIT-CLOSER.

SPECIFICATION forming part of Letters Patent No. 394,413, dated December 11, 1888.

Application filed March 29, 1888. Serial No. 268,882. (No model.)

To all whom it may concern:

Be it known that I, WILLIAM H. SOLEY, a citizen of the United States, and a resident of Philadelphia, Pennsylvania, have invented 5 certain Improvements in Thermostatic Fire-Alarms, of which the following is a specification.

The object of my invention is to so construct an electro-thermostatic fire-alarm as to insure 10 sensitiveness in its operation and to provide for accurately adjusting it for action at any desired temperature. These objects I attain in the manner hereinafter set forth, reference being had to the accompanying drawings, in 15 which—

Figure 1 is a side view of an electro-thermostatic fire-alarm constructed in accordance with my invention; Fig. 2, an inverted plan view of the same.

20 A is a supporting plate or block, which may be secured by means of screws *a* or other equivalent fastenings in any suitable position upon the ceiling, wall, or other portion of the room or apartment to be protected. From this 25 block projects a post, *b*, to which is secured one end of the thermostatic expansion-strip *B*, the latter being composed, as usual, of two strips of metal having different qualities of 30 expansion and contraction under the influence of changes in temperature, this strip being in the form of a loop, the free end of which is jointed to the short arm of a lever, *D*, which is hung to a post, *f*, on the base-block *A*, the long arm of the lever being bent so as to form 35 a finger, *d*, which terminates above the head of a set-screw, *F*, adapted to a threaded stud, *g*, on the block *A*, and secured in position, after adjustment, by means of a lock-nut, *F'*.

At one end of the block *A* are two binding-posts, *x* and *y*, which are connected, respectively, to the positive and negative wires of any suitable battery or other generator of electricity, the post *x* being in electrical connection through a wire, *x'*, with the post *b*, carrying the thermostatic strip *B*, and the post *y* being in electrical connection, through a wire, *y'*, with the stud *g*, carrying the set-screw *F*. The latter thus becomes the terminal of one wire and the lever *D* the terminal of the other wire.

40 The strip *B* is such that the expansion and

contraction of the same, due to variations in the temperature to which it is subjected, cause the free end of the strip to move in the directions pointed out by the arrows 1 and 2, Fig. 1, a fall in temperature causing movement 55 in the direction of the arrow 1 and a rise in temperature causing a movement in the direction of the arrow 2, and this movement being transmitted to the lever *D*, so as to cause the finger *d* at the end of the same to move from 60 or toward the head of the terminal *F*.

If the increase in temperature is such as to bring this finger into contact with said terminal *F*, the circuit is completed from the post *x* to the post *y*, so as to effect the sounding of 65 any appropriate alarm introduced in the circuit.

The use of the lever *D* in connection with the thermostat *B* materially increases the sensitiveness of the apparatus, as, owing to the 70 difference in the length of the two arms of the said lever, movement of the free end of the thermostat is materially increased at the end of the long arm of the lever.

In order to accurately regulate the temperature at which the electrical contact will be made and the alarm sounded, I secure to the block *A* a gage-plate, *J*, to which is hung a lever, *K*, one arm of which is forked and embraces the head of the set-screw *F*, while the 75 other arm is pointed and travels over a graduated scale on the plate *J*, so that on turning the set-screw *F*, so as to raise or lower the same, the pointed end of the lever *K* is caused to travel over the gage and accurately indicate the temperature to which the alarm is set.

The indicator-lever *K* may have a bearing upon but one side of the head of the set-screw *F*, if desired, being kept in contact with the 90 same by means of a spring, as shown by dotted lines in Fig. 1; but the forking of the short arm of the lever for engagement with the head of the set-screw is preferred, as the movement of the lever is thus rendered positive in both 95 directions.

Having thus described my invention, what I claim, and desire to secure by Letters Patent, is—

The combination, in an electro-thermo-

static alarm, of the adjustable terminal connected to one pole, the expansion-thermostat connected to the other pole, a lever, one arm of which is connected to the free end of said 5 thermostat and the other arm adapted to make contact with the terminal, a gage-plate having a scale, and an indicator-lever engaging with and movable by the adjustable terminal, all substantially as specified.

In testimony whereof I have signed my name to this specification in the presence of two subscribing witnesses.

WM. H. SOLEY.
